UNITED STATES PATENT OFFICE.

WILLIAM G. HOUSKEEPER, OF NEW YORK, N. Y., ASSIGNOR TO WESTERN ELECTRIC COMPANY, INCORPORATED, OF NEW YORK, N. Y., A CORPORATION OF NEW YORK.

METHOD AND MEANS FOR FORMING AND WINDING FILAMENTARY MATERIAL.

Application filed May 2, 1919. Serial No. 294,223.

To all whom it may concern:

Be it known that I, WILLIAM G. Hous-
KEEPER, a citizen of the United States, re-
siding at New York, in the county of New
5 York and State of New York, have invented
certain new and useful Improvements in
Methods and Means for Forming and Wind-
ing Filamentary Material, of which the fol-
lowing is a full, clear, concise, and exact de-
10 scription.

This invention relates to a method and
apparatus for winding and forming fila-
mentary material, and particularly filaments
such as are used in electric lamps and
15 audions.

It has for an object to facilitate the
transformation of a long filament into a
plurality of shorter lengths having a de-
sired form, such as M-shaped or V-shaped,
20 for the above purpose.

This object is accomplished by winding
a long filamentary wire or strip of the de-
sired material on a suitable frame, so as
25 to provide a plurality of loops, and cutting
the series of loops along one or more sides
to form the individual filaments in a suit-
able length for use. The series of loops may
be bent into the desired form before or
30 after they are cut according to convenience.

In the preferred form of my invention an
apparatus is provided for making M-
shaped filaments by the above process. The
frame on which the filament is wound is
35 rotatable to facilitate winding, and com-
prises two parts or legs normally in align-
ment but capable of being rotated through
an angle of 180° relatively to each other
when the loops are to be bent.

The invention will be more fully under-
40 stood from the following detailed descrip-
tion and claims taken in connection with
the accompanying drawing in which Fig.
1 is a side elevation partly in section; Fig.
2 is an end elevation showing the wires in
45 position immediately after they are wound
on the frame; Fig. 3 is an end elevation of
the rotating arms showing the wires in
position after the movable pin has been
50 moved into position; Fig. 4 is an end eleva-
tion of part of the device showing the arms
swung around the central shaft to form the

M-shape; Fig. 5 shows the form of filament
desired; and Fig. 6 shows an audion tube
in which such a filament is used.

As shown in the drawing, the winding de- 55
vice comprises a standard 1, provided at its
upper end with a shaft-bearing 2, through
which runs a hollow shaft 3. To one end
of this hollow shaft 3 is fastened a sleeve
4 by means of a set screw 5, the sleeve 60
having integral therewith a handle 6, adapt-
ed to rotate the device. On a reduced di-
ameter of the sleeve 4 adjacent the bearing
2 is mounted a ratchet wheel 7 keyed to
shaft 3, coacting with a pawl 8 which is 65
pivotally mounted on the standard and held
against the ratchet wheel 7 by means of the
action of a spring 9. As viewed in Fig.
1, another sleeve 10 is held to the hollow
shaft 3 on the left of bearing 2 by means 70
of a set screw 11. On the left end of this
sleeve is loosely fastened an arm 12 to the
upper end of which is fastened the winding
cross bar or lug 13 and a locking portion
14 fastened adjacent to the arm 12 and to 75
the lug 13. The lower face of this lock-
ing portion 14 is provided with a shouldered
portion 15 adapted to lock with a corre-
sponding part on another arm to be later de-
scribed. Between the inner face of this 80
arm 12 and the sleeve 10 there is no locking
connection except the action of a ball and
groove mechanism. This mechanism com-
prises a ball 16 spring-pressed within a
hollow portion 17 of the sleeve 10. This 85
ball is normally pressed up against the inner
face of the lower portion of arm 12 and is
adapted to register with a similarly shaped
depression therein. The engagement be-
tween the ball and its groove is sufficient to 90
cause the arm 12 and the shaft 3 to rotate
together except under abnormal conditions.

The left end of shaft 3 is flanged and
closed and on this flanged portion is rigidly
mounted another arm 18 having at its lower 95
end a winding lug 19 and a stop lug 20 and
at its upper end a shouldered portion 21
adapted to coact with the shouldered portion
15 of arm 12. The outer face of arm 18 has
a slight depression where the end of the 100
hollow shaft is situated and in this depres-
sion is placed a plate 22 having projecting

pins 23 thereon which pins serve a function to be later described. This plate 22 also has an aperture therein through which is adapted to slide another pin or fulcrum 24 on the 5 end of sliding plug 25 contained within the hollow portion of the shaft 3. Plug 25 has a portion 26 extending outside the shaft 3 and on the end of this portion is an operating handle 28. This plug is limited in its movements by a stop pin 27 placed at a suitable place within shaft 3.

In Fig. 1 it will be noticed that the pins 23 and the pin fulcrum 24 as shown in the dotted position have considerable length. 15 Likewise do lugs 13 and 19 so that a great many turns of filamentary material may be wound on the frame. As many as forty or fifty filaments have been made on this machine in one single operation. It will be noticed in Fig. 2 that as the wires are wound on the frame the normal area of the wires includes the aperture through which the pin 24 projects. In Fig. 3 however it will be seen how the pin 24 is brought outside the 25 area bounded by the wires. In Fig. 4 is shown the wires bent around to the M-shaped position using pin 24 as a pivot point.

The operation of the machine is as follows:—The end of the filamentary material 30 to be wound and formed is fastened in any suitable manner to the inner edge of one of the lugs, and while the operator holds the filamentary material in the hand the handle 6 is turned to wind the filament upon the 35 frame over the lugs in coils placed side by side. When the required length of material has been wound on the frame the operator cuts off the end and fastens it in any suitable manner. The handle 6 is then turned to 40 bring the frame into the position shown in Fig. 3 so that the two pins 23 will be lying in a horizontal plane and uppermost of the three pins. With the hand the operator then moves the lower strands of the coils up- 45 wardly a sufficient distance so that the pin fulcrum 24 will clear them and lie outside whereupon this pin 24 is moved outwardly by means of the handle 28. The handle's movement is limited by the interposition of 50 the stop pin 27 in the hollow shaft 3. The operator then takes a pair of scissors and cuts the upper strands of the coils between the pins 23. After this the arm 12 is held 55 stationary and pressure is applied to the other arm sufficient to cause the disengagement of the ball 16 from its socket so that arm 18 can be moved around relatively to arm 12 into the position shown in Fig. 4. In 60 this form they are removed from the frame for storage or use. After the wires have been removed from the frame the arms 12 and 18 are moved back into the normal position again until the ball engages with its socket at which time also the shoulders 15 and 21 65 engage and prevent the arms from moving

too far in the other direction. If as shown in Fig. 6, the filamentary material is to be used as the filament in an audion, the portions 29 constitute the upper ends which are suspended by wires 30 and the portions 31 70 constitute the lower ends which are held by wires 32 while the portion 33 constitutes the lower middle portion which is held by a wire 34, when these parts are assembled in the finished audion.

In the audion shown there is a filament electrode 35, a grid electrode 36, and a plate electrode 37 all mounted within an evacuated vessel 38 on a glass arbor 39 which is connected at its lower end to the usual glass 80 press or squash 40.

What is claimed is:

1. The method of winding and forming filamentary material which comprises helically winding a plurality of loops of the 85 material on a frame, disconnecting the loops from each other and so bending each at a single point as to form the loop into an M-shape.

2. The method of winding and forming 90 filamentary material which comprises winding a plurality of loops of the material on a frame, cutting one strand of each of the loops, and bending the other strands of the loops around a fulcrum.

3. The method of winding and forming filamentary material which comprises winding a plurality of substantially flat loops of the material on a frame, cutting one strand of each of the loops, and bending the other strands of the loop around a fulcrum.

4. The method of winding and forming filamentary material which comprises winding a plurality of loops of the material on a frame with an acute angle at their ends, 105 and bending the strands of the loops at their middle points around a fulcrum until they form V-shaped sections.

5. The method of winding and forming filamentary material which comprises winding a plurality of loops of the material on a frame with a desired angle at their ends, 110 cutting one strand of each of the loops, and bending the other strands of the loops around a fulcrum until they form a desired 115 angle.

6. The method of winding and forming filamentary material which comprises winding a plurality of loops of the material on a frame with an acute angle at their ends, 120 and bending the strands of the loops around a fulcrum until they form an equal angle.

7. The method of winding and forming filamentary material which comprises winding a plurality of loops of the material on 125 a frame with a desired angle at their ends, cutting one strand of each of the loops, and bending the strands of the loops at their middle points around a fulcrum until they form an equal angle.

8. A machine for winding and forming filamentary material comprising a frame adapted to receive a plurality of helically wound loops of wire, a fulcrum on said frame, said loops adapted to be bent around said fulcrum.

9. A machine for winding and forming filamentary material comprising a rotatable frame adapted to receive a plurality of loops of wire, a movable fulcrum on said frame, said wires adapted to be bent around said fulcrum.

10. A machine for winding and forming filamentary material comprising a frame adapted to receive a plurality of loops of wire, said frame comprising a pair of oppositely disposed collapsible arms pivoted on said frame, a fulcrum on said frame around which said loops of wire are adapted to be bent when said arms are collapsed.

11. A machine for winding and forming filamentary material comprising a rotatable frame adapted to receive a plurality of loops of wire, said frame comprising a pair of oppositely disposed collapsible arms pivoted on said frame, a movable fulcrum on said frame around which said loops of wire are adapted to be bent when said arms are collapsed.

12. A machine for winding and forming filamentary material comprising a rotatable shaft, a pair of oppositely disposed arms on said shaft, means for latching said arms in their opposed position, lugs on said arm adapted to receive substantially flat loops of filamentary material, a set of stationary pins extending from said shaft and lying within the area bounded by said loops, a movable pin adapted to extend from said shaft and to lie without the area of said loops when one side of the loops is displaced toward the other side, said loops adapted to be bent around said movable pin on one side after the other sides of the loops have been cut adjacent the stationary pins.

13. A machine for winding and forming filamentary material comprising a pair of oppositely disposed arms, lugs on said arms adapted to receive substantially flat loops of filamentary material forming predetermined angles at their end portions, a fulcrum situated near the midportions of said loops around which one side of said loops are adapted to be bent to form an angle equal to the above-mentioned angle, and locking means whereby said arms may be held in opposed relation and may be moved toward each other to bend the loops around said fulcrum.

14. A machine for winding and forming filamentary material comprising a vertical standard having a bearing in its upper end, a hollow rotatable shaft within said bearing, a handle attached to one end of said shaft for rotating the same, a sleeve rigidly at-

tached to the other end of said shaft, a pair of oppositely disposed arms on one end of said shaft adjacent said sleeve, one of said arms being rigidly attached to said shaft, the other of said arms being latched to said sleeve, lugs on said arms adapted to receive substantially flat loops of filamentary material having predetermined angles at their end portions, a pair of stationary pins extending from the end of said shaft and lying within the area bounded by said loops and adjacent one side of said loops, a plug within said hollow shaft having a handle portion at one end and a movable pin at the other, said movable pin adapted to extend through said shafts and to lie without the area bounded by said loops when one side of said loops is displaced slightly toward the other, and means whereby said arms are unlatched and moved toward each other to bend the under side of the loop around said movable pin after the other side of the loops has been cut adjacent the pair of stationary pins.

15. The method of winding and forming vacuum tube filaments which comprises winding a plurality of loops of filamentary material on a frame, and bending said loops around a fulcrum.

16. A machine for winding and forming filamentary material comprising a frame having relatively rotatable portions adapted to receive a plurality of helical loops of material, and a fulcrum around which said loops may be bent.

17. A machine for winding filamentary material comprising a shaft, a plurality of arms mounted for rotation about said shaft, said arms having material receiving portions, and a latch mechanism for determining the angular relations of said arms.

18. A machine for winding filamentary material comprising a shaft, a plurality of arms mounted for rotation about said shaft, said arms having material receiving portions, a latch mechanism for holding the arms in position to receive loops of material and means for collapsing said arms into an abutting relation and thereby bending the loops of material.

19. The method of winding and forming filamentary material which comprises winding a plurality of closed loops of the material on a frame, separating said loops, and collapsing the frame to similarly shape the sections.

20. The method of forming a vacuum tube filament which comprises forming the filament material into an elongated closed loop, severing one strand of said loop midway of the length of said loop and doubling the other strand upon itself in the plane of said loop.

21. The method of winding and forming filamentary material which comprises wind-

ing a plurality of loops of the material, separating said loops and so bending each loop at a single point as to form an M-shaped section from the loop.

5 22. The method of winding and forming filamentary material which comprises winding a plurality of loops of the material on

a frame, bending said loops around a fulcrum on said frame, separating said loops and forming V-shaped sections.

In witness whereof, I hereunto subscribe my name this 29th day of April, A. D., 1919.

WILLIAM G. HOUSKEEPER.
